(57) CLAIM

The ornamental design for a shoe decoration, as shown and described.

DESCRIPTION

FIG. 1 is a perspective view of a shoe decoration, shown in use, showing my new design;

FIG. 2 is another perspective view thereof, with one of the pins in uninstalled condition;

FIG. 3 is another perspective view thereof;

FIG. 4 is a top plan view thereof;

FIG. 5 is a bottom plan view thereof;

FIG. 6 is a front elevation view thereof;

FIG. 7 is a rear elevation view thereof;

FIG. 8 is a right side elevation view thereof, with the left side elevation view being a mirror image thereof; and,

FIG. 9 is a right side elevation view thereof, shown in use.

The broken line portions of FIGS. 1–9 show unclaimed subject matter only and form no part of the claimed design.

1 Claim, 3 Drawing Sheets
